UNITED STATES PATENT OFFICE.

VINTON E. SISSON, OF CHICAGO, ILLINOIS, ASSIGNOR TO UNION METAL PRODUCTS COMPANY, OF CHICAGO, ILLINOIS, A CORPORATION OF DELAWARE.

END STRUCTURE FOR RAILWAY CARS.

Original application filed September 1, 1920, Serial No. 407,316. Divided and this application filed October 1, 1923. Serial No. 665,871.

To all whom it may concern:

Be it known that I, VINTON E. SISSON, residing at Chicago, county of Cook, State of Illinois, and being a citizen of the United States, have invented certain new and useful Improvements in End Structures for Railway Cars, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 This invention relates to improvements in end structures for railway cars and more particularly to sheet metal ends for freight cars.

The end of a freight car is subject to very severe shocks and stresses on account of the tendency of the cargo to shift when the train starts or stops and in switching and also to the tendency of the superstructures of the car to weave while the train is in motion.

30 To strengthen this type of car, ends have been constructed of one or more sheets or panels of metal, usually steel, which sheets or panels are formed with corrugations for rigidifying the structure to more readily meet impacts from without, cargo thrusts from within, and the racking strains from weaving.

It is the object of this invention to provide an end of the sheet metal type which is adaptable to either wooden car frames or all metal freight cars, and that may be employed for strengthening gondola cars, box cars, or other similar cars. It is a further object of this invention to provide the sheets or panels of the end with corrugations of particular contour that from their form and length are peculiarly adapted to meet the stresses and strains already described. While the corrugations are preferably formed parallel, their relation to each other or their direction is immaterial, likewise the corrugations may be all pressed from one side of the sheet of metal or may be formed from opposite sides, as desired.

While the preferred form of this invention is illustrated upon the accompanying sheets of drawings, yet it is understood that minor detail changes may be made without departing from the scope thereof.

In the drawings:

Fig. 1 is an elevation of a box car illustrating an embodiment of this invention.

Fig. 2 is a view in horizontal section taken on line 2-2 of Fig. 1.

Fig. 3 is a view similar to Fig. 2 illustrating the attachment of the end to an all metal box car.

Fig. 4 is an enlarged detail view in vertical section taken on line 4-4 of Fig. 1.

Fig. 5 is an enlarged detail plan view of a fragment of the corner of an end sheet or panel.

Fig. 6 is an enlarged detail sectional view taken on line 6-6 of Fig. 5.

A box car end, as illustrated, comprises two or more sheets or panels 1, preferably of pressed steel, which are attached to the corner post, end plate and end sill 21 in the usual manner.

Fig. 2 illustrates a means of attaching the panels to a wooden corner post 20 by flanging the ends of the panel and securing the flanges to the post.

A plurality of parallel strengthening corrugations are formed in each panel and merged at their ends into the plane of the panel so that the panel has a flat marginal portion about its edges. The particular contour of the corrugation is illustrated in the large sectional view of Fig. 4. It is to be noted that each corrugation is formed with main walls 4 substantially at right angles to the plane of the panel, which are connected by curved arched portions 5. Each corrugation is wider than the distance 30 between parallel planes 31 and 32 drawn through the outermost parts of the corrugated panel. The greater the distance between the main walls 4, the greater the width of the connecting portions 5, and consequently more metal is positioned away from the neutral axis of the section, resulting in a higher section modulus, meaning, of course, a stronger corrugation, theoretically. The connecting portion (5) is a (secondary) beam and must transmit the load imposed upon it to the main walls 4-4. In actual practice, a flat connecting portion will deflect and not per-

form its function if the main walls are spaced very far apart. The apexed or arched construction increases the capacity of the connecting member to transmit thrusts to the adjacent main walls and thereby permits the main walls to be spaced further apart, thus obtaining a higher section modulus, as stated above.

The width of each corrugation is preferably constant throughout the major portion of its length and the depth also preferably remains constant the greater part of its length but gradually diminishes at each end until the corrugation merges into the plane of the panel, as shown in Figs. 5 and 6.

A wooden end lining 6 is preferably provided on the inner side of the end panel and a plurality of filler blocks or nailing strips are received within and attached (by bolts 8) to a number of the corrugations, as shown in Fig. 4, to which the wooden lining is nailed.

In theory the ideal form of corrugation for this purpose would have flat main walls extending perpendicular to the plane of the panel as having the greatest strength to resist the stresses imposed on car ends. In practice, in pressing corrugations from a panel by dies, it is very difficult to form the main walls in this relation. The curved arched portion 5 between the walls 4 act in the manner of an arch or bridge whereby the stresses occurring at the apex are distributed through the arched portions to the main walls which, as above stated, are most advantageously arranged to meet such stresses. The majority of impacts received by the end of the car are from within and are caused by the shifting of the cargo. The cargo thrusts are first received on the wooden lining 6 of the end, and as this lining is continuous and is in contact with the apexes of the respective corrugations, the thrust will be transmitted from the lining 6 through the arched portions 5 of the corrugations and be distributed through the main walls 4. The lining 6 distributes the shock of the shifting lading to the several corrugations. However, even if the lining were not present the arched portions 5 would distribute the stresses to the main walls 4.

This is a division of my co-pending application Serial No. 407,316, filed September 1, 1920.

I claim:

1. A metallic panel for car ends having a plurality of corrugations formed therein with main walls, and curved arched portions connecting said main walls, the width of each corrugation being greater than the distance between parallel planes drawn

through the outermost parts of the corrugated panel.

2. A metallic panel for car ends having a plurality of corrugations formed therein of constant width throughout the major portion of their length, said corrugations having main walls, and curved arched portions connecting said main walls, the width of each corrugation being greater than the distance between parallel planes drawn through the outermost parts of the corrugated panel.

3. A metallic panel for car ends having a plurality of corrugations formed therein of constant width throughout the major portion of their length, and merged into the panel at their ends, said corrugations having main walls, and curved arched portions connecting said main walls, the width of each corrugation being greater than the distance between parallel planes drawn through the outermost parts of the corrugated panel.

4. A metallic panel for car ends having a plurality of parallel corrugations formed therein spaced apart distances equal to their width, said corrugations having main walls, and curved arched portions connecting said main walls, the width of each corrugation being greater than the distance between parallel planes drawn through the outermost parts of the corrugated panel.

5. An end structure for railway cars comprising a plurality of metallic panels, corner post, and means for attaching the panels to the post, said panels being formed with a plurality of corrugations having main walls, and curved arched portions connecting said main walls, the width of each corrugation being greater than the distance between parallel planes drawn through the outermost parts of the corrugated panel, and an end lining on the inner side engaging the arched portions of the respective corrugations.

6. An end structure for railway cars comprising a plurality of metallic panels, corner post, and means for attaching the panels to the post, said panels being formed with a plurality of corrugations having main walls, and curved arched portions connecting said main walls, the width of each corrugation being greater than the distance between parallel planes drawn through the outermost parts of the corrugated panel, an end lining on the inner side engaging the arched portions of the respective corrugations, and filler blocks received within and secured to some of the corrugations for attaching the lining to the panel.
